DESIGN FOR A PUMP BODY

John A. Murnane, Waterbury, Conn., assignor to
Chase Brass & Copper Co. Incorporated,
Waterbury, Conn., a corporation

Application January 2, 1940, Serial No. 89,259

Term of patent 7 years

To all whom it may concern:

Be it known that I, John A. Murnane, a citizen of the United States, residing at Waterbury, in the county of New Haven and State of Connecticut, have invented a new, original, and ornamental Design for a Pump Body, of which the following is a specification, reference being had to the accompanying drawing, forming part thereof.

Fig. 1 is a perspective view of a pump body showing my new design; and

Fig. 2 is a front face view of the same.

The characteristic feature of the design resides in the bullet-like upper terminal having the configuration shown.

I claim:

The ornamental design for a pump body, substantially as shown and described.

JOHN A. MURNANE.
